UNITED STATES PATENT OFFICE.

GEORGE E. SOVEREIGN, OF POTTERSVILLE, NEW JERSEY.

APPARATUS AND METHOD FOR SHREDDING LEATHER.

No. 845,721.

Specification of Letters Patent.

Patented Feb. 26, 1907.

Application filed August 21, 1906. Serial No. 331,446.

To all whom it may concern:

Be it known that I, GEORGE E. SOVEREIGN, a citizen of the United States, residing at Pottersville, in the county of Hunterdon and State of New Jersey, have invented certain new and useful Improvements in Apparatus and Methods for Shredding Leather, of which the following is a specification.

The objects of this invention are to provide means for reducing or shredding scrap and waste leather, so that the same may be utilized for leather-board and the like by mixing with other proper ingredients and pressing; to reduce or shred the leather so that it will be of a long fibrous character and not pulverized; to this end to provide shredding-plates which will act upon the leather gradually as it passes between the same; to prevent the clogging of said plates and insure onward movement of the leather; to provide for a proper separation of the products of shredding as they come from the said plates, whereby only the useful fibrous material is preserved apart from the granular particles; to avoid the danger of setting fire to the reduced product in the mill; to do this by mixing the shredded fiber directly as it comes from the reducing-plates with water as one of the steps toward forming leather-board of it; to thus facilitate and simplify the process of making leather-board; to secure an improved product at less labor and expense, and to obtain other advantages and results as may be brought out in the following description.

Referring to the accompanying drawings, in which like numerals of reference indicate corresponding parts in each of the several figures, Figure 1 is a side elevation of an apparatus of my improved construction for shredding leather, the reducing-plates being shown in central cross-section and the lower separating portion of the mill being in perspective and partly broken away to show its construction more clearly. Fig. 2 shows in plan the coöoperating faces of the two shredding plates or disks on a larger scale. Fig. 3 is an edge view of the segmental portion of said plates included between the chordal lines *x* and *y*, Fig. 2. Fig. 4 is a view similar to Fig. 3, illustrating a modified construction. Fig. 5 is a view similar to Fig. 1, illustrating a modified method of separating the products of the mill after they have been reduced or shredded. Fig. 6 shows in perspective a water bath or tank into which the

products of the shredding-plates are discharged. Fig. 7 illustrates a method of sprinkling the products of the reducing or shredding plates as they emerge therefrom, 60 and Fig. 8 shows modified means for mixing the product of the mill with water as a protection against fire and a step toward mixing the same for the manufacture of leather-board or the like. Fig. 9 illustrates means 65 for drying the product of my shredding-plates in the mill, and Fig. 10 shows other means for accomplishing this same result.

In said drawings, 1 indicates the base or frame of a shredding mill or machine adapted to be located as upon a floor 2, said frame providing bearings 3 3 for shafts 4 4, arranged in alinement with their ends adjacent and adapted to be driven in opposite directions, as by means of pulleys 5 5. Said frame provides an upwardly-extending casing 6, which is adapted to inclose circular heads 7 8, arranged upon the adjacent shaft ends in substantially parallel relation. Upon the inner facing sides of said heads 7 8 are located annular shredding plates or disks 9 10, hereinafter more particularly described, and below the said heads 7 8 a discharge passage or aperture 11 is provided through the floor 2. At the upper part of the casing 6 is arranged a hopper 12, through which the leather scrap or chips is fed to the mill, the lower part of said hopper opening, as by a passage 13, against the central portion of one of the reducing-heads, said reducing-head 90 having in from its shredding-plate an aperture 14 to receive from said hopper a supply of the fibrous material to be ground.

From its entrance between the reducing heads 7 8, as just described, the stock is 95 thrown radially outward by centrifugal force to the shredding plates or disks. These disks provide in cross-section, as shown, a reducing-passage for the leather, which tapers or is reduced outwardly, as shown, whereby the 100 stock or small pieces of leather enter between the shredding-disks readily, and yet as they are reduced in size by the tearing of shreds or fibers from their exterior they do not, because of the reduced passage-way, 105 pass through the shredding-plates without being sufficiently acted upon. Obviously the discharge of material from the shredding-plates is at their peripheries.

Referring now more particularly to Figs. 2 110 and 3 of the drawings, it will be observed that each of the shredding-plates 9 and 10

- has a body portion 15 and that the inner faces of said body portions are inclined along radial lines of the plates toward each other. The said inclined surface of each shredding-disk is then provided with radial ribs, which are sharp at their side edges to provide cutting or reducing surfaces, and, as will be seen from the drawings, there are several different lengths of said ribs, or, in other words, they do not all terminate at the same distance from the inner edge of the annular plate, although they do all terminate at the outer edge of the plate. These ribs are of uniform height, so as to provide for the reducing-passage the same incline as do the disk-faces of the shredding-plates themselves. The shredding-plates 9 10 are, furthermore, provided with annular ribs or flanges 25, which cut across the radial ribs just described, the plate 10 having two such annular ribs, one of which, as 16, is at the extreme edge of the plate, while the other, 17, is at a little distance inward therefrom, and the other plate, 9, having three annular ribs, one of which, as 18, is at the extreme edge of the disk, another, 19, sufficiently near thereto to lie between the ribs 16 and 17 of the plate 10 when the two plates coöperate, and the third, 20, is near enough the center of the disk to alternate with said rib 17 of the plate 10 on the other side thereof from the rib 19 when the two plates are placed together. As the particles of leather travel radially of the plates, therefore, they are forced to take a tortuous passage between the said annular ribs 16 to 20, and thus be constantly exposing themselves to the cutting action of the radial ribs, as will be understood. The entrance to the passages between the shredding-plates is too small to allow the pieces or chips of leather to hide between the ribs and escape shredding, and the space between the oppositely-coinciding outer annular ribs 17 and 20 gages the size of the fibers with respect to coarseness or fineness. This tapered relation of the shredding-plates 9 and 10 is of especial importance because of the nature of the substance or leather to be acted upon. If the passage were uniform and the entrance large enough to admit the chips and scraps of leather, the fibers of the reduced product would not be sufficiently fine to serve the purpose of my invention, and, on the other hand, if the outer edges of the plates were near enough together to secure fineness the inner edges would not admit the leather to be shredded.
- Instead of forming the body portions of the shredding-plates with inclined surfaces upon which ribs of uniform height are located I may, as shown in Fig. 4, employ plates 21 22, whose faces are parallel at their body portions and are provided with radial ribs 23, which increase in height outwardly or toward the periphery of the plates. Obviously this construction also provides a tapered passage-

way for the leather being reduced and also in a marked degree increases the space available to be occupied by the leather as it passes through the shredding-plates, such increase being due not only to the widening of the spaces between the ribs, but also to the increased depth of the ribs outwardly. Clogging or jamming of the machine or mill is thus not likely to occur.

The reduced product leaves the shredding-plates at their lower peripheral points and escapes by the passage-way 11 through an opening 30 in the floor 2, where in Fig. 1 I have shown it received by a passage 31, leading downward to a screen or sieve 32, said sieve being adapted to be reciprocated by means of a cam 33 on a shaft 34, driven by a pulley 35 and adapted to engage the said sieve. Said sieve is suspended by links 36 to enable it to move freely, and obviously only the coarser fibrous pieces will be retained by said screen, the fine dust-like or granular particles passing through the screen to fall beneath the same, where they can be carted away as refuse or for other purposes than making leather-board.

It will be observed that the material passes very directly from the shredding-chamber to the separating-screen 32, the passage 31 being as straight and direct as possible and preferably being practically vertical. Down this passage 31 the material is carried not only by gravity, but also by the air-current in said passage, for it will be understood that the rapidly-revolving reducing-heads 7 and 8 act in a measure as a centrifugal blower, inducing a strong blast of air which sweeps the shredding-chamber clear of the ground material and carries it down the passage 31 upon the screen 32. Owing to the natural tendency of the ground material to pack or settle compactly together, it is highly important that the separation of the coarser particles from the dust and fine particles shall be accomplished before the settling or packing has taken place, for once the material has become compacted it is practically impossible to screen or sift it thoroughly. It will be understood that this settling or packing is of necessity a somewhat gradual process, the finer particles gradually sifting or dropping down between the coarser particles. Also in the case of particles carried by a current of air, as is the case here, each particle has adhering to it an envelop of air which persists for a moment after the mass of accumulated material at the bottom of the passage is reached, the several particles being buoyed up for a moment by the air, then separating from the solid material, and the mass being in a much more open condition than it will be if allowed to stand for a moment. These conditions all favor separation of the coarse material from the fine material, provided the separation be effected at once; but to utilize these favorable

conditions the separating device must be in direct connection with the shredding-mill, as is the case in the apparatus shown, and must not be connected indirectly or in such manner that considerable time will elapse before the ground material reaches the separating device.

Instead of the reciprocating screen just described I may employ, as shown in Fig. 5, an exhaust or fan 37, which separates the desirable fibrous part of the product from the fine powdered portion and conveys it to any desired point for further operations, some of which may be hereinafter referred to. To this end I have shown a vertical passage 38, leading downward from the floor 2 and provided at one side with a lateral branch 39 in communication with the said fan 37. By regulation of the fan, therefore, the fibrous portion of the reduced product is separated just after leaving the shredding-plates and before it has settled anywhere or been allowed to conglomerate in any degree. The blower 37 further conducts the fibrous product through the tube 39 to any desired point. Gates 40 and 41 in the passage 38 control the air-currents so as to regulate the separation of the products of shredding, and the waste or residue falls upon the floor at the bottom 30 of the vertical portion 38.

In Fig. 6 I have shown a tube or passage-way 26, leading from the reducing-mill and through which the products of shredding are delivered beneath the surface of the water in a tank or water-bath 27. This obviates any danger of the light and somewhat inflammable material becoming ignited by any kind of inadvertent friction in the mill or machine—as, for instance, the presence of a match-head or the like. The product is discharged directly into water and can then be separated or assorted in any suitable manner, as by passing the liquid compound through screens, taking advantage of the settling of the particles or in any other suitable way. If separating is dispensed with or if the introduction of the fibrous product into water is subsequent to its separation, as already described, obviously this mixing with water 50 can be utilized as one of the first steps in the process of making up the reduced fiber into leather-board. If this latter was done, other liquids than water could be employed, as desired.

In Fig. 7 I have shown a construction where the reduced product on emerging from a delivery-tube 42 is subjected to streams 43 from a sprinkler 44, which acts on the principle of a shower-bath and thoroughly moistens the entire pile 45 of fibrous leather. Said sprinkler 44 is preferably mounted upon the tube 42 by braces 46, and water is supplied thereto by a supply-pipe 47.

In Fig. 8 I have shown the discharge-tube

50 for the reduced leather as terminating at 65 or near the surface of the water in a tank 51. Pipes 52 lead into the said discharge-tube 50 back from its mouth and serve to thoroughly sprinkle the interior of the same, as shown at 53. The shredded leather is 70 thus moistened as it comes from the mill and, furthermore, is discharged into the tank 51. Supply-pipes 54 open into the tank 51, said tank being also provided with opposite outlets 55, so that a distinct current is produced 75 to carry the fibrous leather away from the tube 50 into all parts of the tank.

It will be understood that one important feature of my invention is the acting upon the reduced product immediately as it issues 80 from the shredding-plates before it has had a chance to settle anywhere and become matted or compacted into a mass. This acting upon the shredded product may be to separate the same or to sprinkle the same or to 85 otherwise prepare it for further operations in the manufacture of leather-board. Various modifications may be made in carrying out this idea either as to the construction of apparatus employed or to the details of the 90 method followed, and I therefore do not wish to be understood as having limited myself by any of the positive descriptive terms herein employed.

In case the separation of the products of 95 my improved shredding is made dry, as shown in Figs. 1 and 5, I may in conjunction with the same subject such products to a drying process in order to enable them to be safely packed or handled on quantity, and 100 this feature of my invention I have illustrated in Figs. 9 and 10.

In Fig. 9, 56 indicates the screen from which the shredded material is discharged, and 57 is a conveyer-belt adapted to receive 105 the material from said screen, said belt being heated by means of steam-pipes 58 or other equivalent means. Preferably the said drier-belt is inclosed in the chamber of a casing 59, and which chamber can be further heated by 110 pipes 60 therein. The shredded products are thus dried upon the belt 57 in their separated condition as they come from the screen 56 and may be delivered from the opposite end of the conveyer-belt in any suitable manner desired.

In Fig. 10, 61 indicates an exhaust-separator of the type shown in Fig. 5 and through the delivery-tube 62 of which the separated shreds are to be delivered. I have shown a 115 portion of said tube 62 as heated, so that the shreds of leather in their passage therethrough will be dried, as will be understood. A burner 63, providing a series of gas-jets, is shown for such heating, although obviously 120 any other suitable means could be employed equally well. Straps 64 serve to support the tube 62. In continuation of this feature of

drying the shredded leather it should be noted that the exhaust-fan or blower could be operated wholly in heated air, so as to both convey and dry the product simultaneously.

Having thus described my invention, what I claim is—

1. In a shredding-mill, the combination of rotary shredding-plates the faces of which are opposed relatively, said plates having in such faces radial ribs and annular ribs intersecting a plurality of said radial ribs, the radial ribs of the two plates forming a space narrowing progressively toward the peripheries of the plates, the annular ribs of the two plates relatively staggered.
2. A shredding-disk provided on its face with a plurality of radial ribs of height increasing progressively toward the periphery of the disk, and with ribs crossing said radial ribs transversely.
3. In a shredding-mill, the combination of rotary shredding-plates the faces of which are opposed relatively, said plates having on their faces approximately radial ribs, the ribs of the two plates progressively approaching each other toward the peripheries of the plates, and having other ribs crossing said radial ribs transversely, such transverse ribs of the two plates relatively staggered.
4. In a shredding-mill, the combination of rotary shredding-plates having faces opposed relatively and approaching each other toward the peripheries of said plates, said plates having in such surfaces or faces radial ribs and annular circular ribs concentric with the axis of rotation of said plates, the annular ribs of the two plates relatively staggered.
5. In a leather-shredding machine, the combination of opposite annular shredding-plates having body portions which provide at their facing sides parallel surfaces, radial ribs upon said parallel faces each increasing in height from the center of the plate outwardly, whereby outwardly-converging reducing surfaces are provided by the two shredding-plates, and at the same time the radial ribs provide pockets, between the ribs, annular ribs or flanges intersecting said radial ribs, and means for driving the shredding-plates in opposite directions.
6. In a leather-shredding machine, the combination of a closed shredding-chamber, rotary shredding means therein comprising means producing an air-draft therethrough, a passage conveying the product from said chamber, and product-assorting means arranged transversely with respect to said pas-

sage and in line therewith and receiving the discharge therefrom.

7. In a leather-shredding machine, the combination of a closed shredding-chamber, rotary shredding means therein comprising rotary disks having means for producing an air-draft therethrough, a passage extending downward from said chamber, and product-assorting means arranged transversely with respect to said passage and in line therewith and receiving the discharge therefrom.

8. In a leather-shredding machine, the combination of a shredding-chamber, opposed rotary shredding-plates therein toothed on their adjacent faces, a separating-screen, means for operating the same, and a passage leading directly from said chamber to said screen.

9. In a leather-shredding machine, the combination of a shredding-chamber, opposed rotary shredding-plates therein toothed on their adjacent faces, a separating-screen, means for vibrating the same, and a passage leading directly and immediately from said chamber to said screen.

10. In a leather-shredding machine, the combination of a shredding-chamber, rotary opposed shredding-plates therein toothed on their adjacent surfaces, a separating-screen beneath said chamber, means for vibrating said screen, and a substantially vertical passage leading directly from said chamber to said screen.

11. The herein-described method of shredding and assorting the product which consists in subjecting the desired material to a shredding action, conducting the material shredded away and before packing or settling of the material can occur subjecting it to a separating and assorting action.

12. The herein-described method of shredding and assorting the product which consists in subjecting a material to be treated to a shredding action, conveying the shredded product away in aerial suspension and while still in such suspension subjecting it to an assorting and separating action.

13. The herein-described method of shredding and assorting the product which consists in subjecting material to be treated to a shredding action and immediately thereafter and before packing or settling can occur screening it.

GEORGE E. SOVEREIGN.

In presence of—

RUSSELL M. EVERETT,
ETHEL B. RIED.
